[57] CLAIM

The ornamental design for a support stand for a loudspeaker, substantially as shown.

DESCRIPTION

FIG. 1 is a perspective illustration of the speaker stand;
FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a perspective view thereof in normal position
for use, a second support stand being shown in broken
lines for illustrative purposes only.
